To all whom it may concern:

Be it known that I, James B. Mutch, a citizen of the United States, residing at Rochester, in the county of Monroe and State of New York, have invented a new, original, and ornamental Design for a Shoe Tree, of which the following is a specification, reference being had to the accompanying drawing, forming a part thereof, and in which:

My design for shoe tree, as shown, is characterized by its upper forward toe portion presenting uninterrupted smooth curved lines from side to side and from the rear end to front end thereof, a round connecting bar having one end extending from an elongated groove in the flat face of the rear smooth vertically disposed wall of the toe portion, and a rounded tapered heel piece attached to the other end of the round connecting bar.

I claim:

The ornamental design for a shoe tree, as shown and described.
